UNITED STATES PATENT OFFICE.

WILLIAM HENRY HARRINGTON, OF HARTFORD, CONNECTICUT, ASSIGNOR TO THE ARROW ELECTRIC COMPANY, OF HARTFORD, CONNECTICUT, A CORPORATION OF CONNECTICUT.

DESIGN FOR A HANDLE FOR ELECTRIC SWITCH OR SIMILAR ARTICLE.

Application filed February 6, 1925. Serial No. 12,284. Term of patent 14 years.

To all whom it may concern:

Be it known that I, WILLIAM HENRY HARRINGTON, a citizen of the United States of America, residing at Hartford, in the county of Hartford and State of Connecticut, have invented a new, original, and ornamental Design for Handle for Electric Switch or Similar Article, of which the following is a specification, reference being had to the accompanying drawings, forming part thereof.

Figure 1 is a side elevation of a handle for electric switch, embodying my new design.

Figure 2 is a plan view from above.

Figure 3 is a rear elevation.

I claim:

The ornamental design for a handle for electric switch or similar article, as shown.

WILLIAM HENRY HARRINGTON.
